UNITED STATES PATENT OFFICE.

ROBERT L. LYONS, OF WALTHAM, MASSACHUSETTS.

SEWING-MACHINE.

1,160,423.

Specification of Letters Patent. Patented Nov. 16, 1915.

Application filed April 8, 1912. Serial No. 689,221.

To all whom it may concern:

Be it known that I, ROBERT L. LYONS, of Waltham, in the county of Middlesex and State of Massachusetts, have invented certain new and useful Improvements in Sewing-Machines, of which the following is a specification, reference being had to the accompanying drawings, forming part thereof.

This invention has reference to improvements in sewing machines and particularly in button sewing machines.

The main object of this invention is to so construct a sewing machine that two superposed buttons may be secured by sewing stitches, that the sewing thread may be knotted close to lower of said buttons, and that said knotted thread may be parted close to or in said knot.

Other objects of this invention will appear from the following description.

The invention consists in the novel means for holding the buttons during the sewing operation.

The invention also consists in such other novel features of construction and combination of parts as shall hereinafter be more fully described and pointed out in the claims.

Figure 1 represents a side elevation of a sewing machine, partially broken away and partially shown in section, illustrating the new invention, Fig. 2 represents end view of portions thereof partially in section as taken on line 2—2 Fig. 1. Fig. 3 represents a plan sectional view of the same as taken on line 3—3 Fig. 1. Fig. 4 represents a sectional view of the product of this machine.

Similar numbers of reference designate corresponding parts throughout.

In carrying this invention into practice my main object has been to so construct a sewing machine that a button and a localized stay or strengthening member or device, preferably a second button, may be simultaneously attached by sewing stitches to an interposed fabric whereby the button is more effectually secured as the stay prevents the stitches from being pulled through the fabric when the button is manipulated to engage and disengage the same from a button hole. In order to facilitate this operation it is essential to distinguish, as regards the broad aspects of the invention, from the heretofore well known method of sewing on buttons in which a button is sewn to the

outer surface of a fabric and in which the button holding means is usually so related to the fabric that the button can be readily adjusted and held with respect to the path of the needle that it is not material whether the relative vibratory movement of the button and the stitch forming means, alternately to present the holes of the button in the path of the needle is accomplished by reason of the vibration of the button or of the stitch forming means.

In order to localize the stay, particularly when such stay is formed by a button, it is essential that the stay and the button should be positively placed and held with their thread receiving holes or perforations in registry and that subsequent to such placing of the buttons the fabric to which they are to be sewn should be inserted and supported therebetween. By reason of these essentials I have found the ordinary vibratory button clamp to be impractical and that the necessary duplex button holding and fabric supporting means should be stationary with respect to the vibration of the stitch forming devices. I find also that the placing and adjusting of the stay and the fabric are facilitated by the mechanism herein described and that the stay and button are more satisfactorily secured by tying a knot in the thread close to the stay and then parting the thread near or in said knot.

In its preferred form I have illustrated this invention as applied to a single thread sewing machine of known construction in which 5 indicates the base having the extension 6 and furnished with the frame 7 carrying the head 8 which has the guide 9 for the slide rod 10 of the needle bar guide 11 in which the needle bar 12 is vertically slidable, any usual mechanism being employed to effect the operation of the needle bar. Slide rod 10 is carried by the post 13 of the carriage 14 which is slidable in guides 15, 15 of the extension 6 and has depending fingers as 16. Provision is made for effecting the vibration of carriage 14 and such vibration is transmitted by the fingers as 16 to the looper shaft 17 rotatably mounted in said base extension 6 and having the collars 18 and 19, between which the fingers as 16 are engaged, and to the looper 20 and the collar 21 which latter is engaged in a groove of the slideable thread positioning plate 22 having the thread passage 23 and of well 110

known construction. Provision is made for driving the looper shaft 17 from the drive shaft 24 by means of the pinions 25 and 26.

Extension 6 has the throat plate 27 having the throat 28, Fig. 2, and on this throat plate is mounted the stay holder and localizer, and fabric support comprising two jaws 29 and 30 of which jaw 29 is adjustable but preferably fixed after adjustment, while jaw 30 is slidable, the operation of this latter jaw being effected through the shaft 31 journaled in arms, extending from the base extension 6, and having the retracting spring 32, the actuating arm 33 and the collar 34 in which is engaged the pin 35 which is connected with the sliding jaw 30.

Presser foot rod 36 is slidably mounted in the head 8 and has at its lower end a button holding clamp or device preferably having the arms 37, 37. The upward movement of this rod 36 is effected by means of the arm 38 of shaft 39 which latter is journaled in bearings provided on the frame 7 and is furnished with the arms 40 and 41, the thread puller arms 42 and 43, and the cam 44, of which arm 40 is connected with arm 33 of shaft 31 by the chain 45 so that the initial rotative movement of shaft 39 is transmitted through said chain to effect a rotation of shaft 31 and through pin 35 to move the stay holding jaw 30 in the releasing direction simultaneously with or slightly prior to the upward movement of rod 36 and its button clamp.

On frame 7 are mounted the ordinary thread tension 46 the thread guides 47 and 48 and a thread clamping device comprising the fixed member 49 and the post 50 carrying the pivoted clamping member 51 which co-operates with said member 49 and is actuated by the rod 52 slidably in guides extending from the frame 7 and having the pin 53 bearing on and adapted to be lifted by cam 44 of shaft 39 when said shaft is rotated by power applied to arm 41 thereof through rod 54.

In preparing this improved machine for operation the thread T—T is passed through the tension 46 through guides 47 and 48, between the members 49 and 51 of the clamping device and ultimately to and through the eye of the needle N carried by the needle bar 12. The jaws 29 and 30 are adjusted to hold a stay, in the present instance the inverted button S, between them and resting on the throat plate 27 with its holes above the throat 28 and located in the predetermined paths assumed by the needle in its lateral vibration; this placing of the stay S is effected when the button clamp of rod 36 is in the elevated position. The main button B is now placed between the arms 37, 37 of the upper clamp and adjusted and the fabric F is placed on the jaws 29 and 30, beneath the button B, whereby the upper sur-

faces of said jaws act as a fabric support. Rod 36 is now permitted to move downward until the button B carried by its clamp rests against the fabric and, during such movement the jaw 30 completes its inward movement to engage and hold the stay S. The machine is now started and a series of stitches is formed through the button B, fabric F, and stay S, and the lateral vibration of the needle is prevented during two or more loop delivery movements thereof whereby a series of chain loops are formed and the machine is brought to a stop with said chain loops drawn into a knot, so called close to the face of the inverted stay S. Rod 54 is now actuated to rotate shaft 39 and results in the operation of thread puller arm 43 to draw a supply of thread through tension 46, the lifting of rod 52 by cam 44 to clamp the thread between the clamping members 49 and 51, the actuation of thread puller arm 42 to draw back slack thread after such clamping and the actuation of shaft 31, through arms 33 and 40, and chain 45 to move the stay holding jaw 30 in the releasing direction approximately simultaneously with the upward movement of rod 36 and its button clamp whereby strain is put on the clamped thread, with the result that said thread breaks in or close to the knot formed at the face of stay S.

While I have herein illustrated my invention as carried into operation by simple but practical mechanism it is not my intention to limit this invention to any specific features of construction.

Having thus described my invention I claim as new and desire to receive by Letters Patent.

1. A button sewing machine comprising in combination a stay button clamp having a pair of stay-engaging members one of which is adapted to be fixed and the other of which is movable, and a main button clamp movable at right angles to said stay button clamp and having button holding arms.

2. A button sewing machine comprising in combination a stay button clamp having a slidable member, a main button clamp movable with respect to said stay clamp, and means for moving said main clamp and the slidable member of the stay clamp approximately simultaneously.

3. A button clamp comprising in combination a stay button clamp having a pair of flat holding members forming a fabric support of which one member is movable, means for moving said movable member in the releasing direction, a main button clamp movably mounted above said stay clamp, and means for moving said main clamp.

4. The combination with a throat plate, of a pair of holding jaws mounted above said plate, and a presser foot button clamp movably mounted above said jaws.

5. A button sewing machine comprising in combination a throat plate, a pair of button holding jaws, one of which is movably mounted on said throat plate, a vertically 5
slidable rod, a button clamp carried by said rod, and means for moving said rod and said movable jaw approximately simultaneously.

6. A button sewing machine comprising 10 in combination means for supporting two superposed buttons at the sides of an interposed fabric, stitch forming means, thread clamping means, and mechanism for releasing one of said button holding means and 15 for moving the other button holding means to strain the thread.

7. A button sewing machine comprising in combination a throat plate, jaws mounted thereon, one of which is movable, a shaft

rotatably mounted, means actuated by the 20 rotation of said shaft for moving said movable jaw, a presser foot rod slidably mounted, a button clamp on said rod, and mechanism for moving said rod and approximately 25 simultaneously therewith effecting the rotary movement of such shaft.

8. A button sewing machine comprising in combination, a releasable stay-holding means forming a fabric support, a button holding presser foot, mechanism for operating 30 said stay holding means to release the stay and for operating said presser foot to thereafter break the thread.

ROBERT L. LYONS.
